UNITED STATES PATENT OFFICE.

CHARLES BURNHAM, OF LOS ANGELES, CALIFORNIA, ASSIGNOR TO BURNHAM BASKET COMPANY, A CORPORATION OF CALIFORNIA.

BOX-MAKING MACHINE.

1,194,815.

Specification of Letters Patent. Patented Aug. 15, 1916.

Application filed February 4, 1915. Serial No. 6,109.

To all whom it may concern:

Be it known that I, CHARLES BURNHAM, a citizen of the United States, and a resident of Los Angeles, county of Los Angeles 5 and State of California, have invented certain new and useful Improvements in Box-Making Machines, of which the following is a full, clear, and exact description.

This invention relates more particularly 10 to the punch and die mechanism of a machine for making berry or fruit baskets such as shown in my pending application, Serial No. 734,155, filed November 29, 1912.

One of the principal objects of the invention 15 is to provide means whereby shooks of veneer or other material may be supported crosswise and folded into box form without the necessity for scoring the shooks and without causing or permitting the shooks 20 when of wood to break or sliver at the point of folding particularly where the shooks, as is often the case, are cross-grained, and which means during the folding operation will move the box body in its folded form 25 in position to receive a metal or other suitable binding to complete the box.

Another object of the invention is to provide yieldingly held wings as a part of the die mechanism and which so co-act with 30 other parts of the die that during the folding the shooks or body material will be positively held at the point of folding and the wings made to lap or slide at such folding point, thus making a perfect fold.

Other objects of the invention are to provide the die with yielding parts which will 35 compensate for any error in lengths of the shooks and which will feed the shooks if of uneven lengths properly into the binding rim and hold the same while the bottom of the basket takes care of the error in the difference in lengths of the shooks and still allow a good basket to be made; to provide simple means for absorbing the 40 inaccuracies in alinement and also any difference in the thickness of the wood or other shooks; and to provide adjustments between the several parts of the die mechanism and to hold the same against improper movement.

A further object of the invention is to provide a simple and effective plunger or punch which is adapted to coöperate with the die, and which assists in forming the box body

and further assists in stripping the box body 55 when formed.

A still further object of the invention is to provide simple means whereby parts of the plunger or punch mechanism may be removed for repairs or for other purposes. 60

A still further object of the invention is to provide simple and efficient means whereby suction may be created or destroyed in a part of the die to assist in stripping the box when formed from the punch and keep the 65 box down in the die and place the same in position for removal from the machine.

A still further object of the invention is to provide simple and efficient means for holding the shooks crosswise for removal 70 and folding by the punch and die.

With these and other objects in view, the invention will be hereinafter more particularly described with reference to the accompanying drawings, which form a part of 75 this specification, and will then be pointed out in the claims at the end of the description.

In the drawings, Figure 1 is a vertical section, partly in elevation, of one form of 80 punch and die and mechanism embodying one form of my invention and showing a shook holder or carrier located between the punch and die for supporting the shooks crosswise of each other. Fig. 2 is a fragmentary vertical section showing one form of means for creating suction in the die. Fig. 3 is a view similar to Fig. 2 except that the parts are in a different position. Fig. 4 is an enlarged vertical section, partly broken 85 away and partly in elevation, of the die and mechanism shown in Fig. 1. Fig. 5 is a fragmentary section showing a form of adjustment between certain parts of the die mechanism. Fig. 6 is a fragmentary side 90 elevation of the adjusting means shown in Fig. 5. Fig. 7 is a vertical section taken on the line VII—VII of Fig. 5 showing how the adjustable links are held spaced apart in pairs. Fig. 8 is a plan view, partly in 100 section and partly broken away, of the die and its mechanism and the guide frame for the die. Fig. 9 is a sectional plan taken on the line IX—IX of Fig. 4. Fig. 10 is an enlarged vertical section, partly broken 105 away, showing the punch or plunger and the die in position after the shooks have been folded into box form, the position of some

- of the parts being somewhat exaggerated for illustrative purposes. Fig. 10^a is a fragmentary section showing how the mechanism may be made to clench the metal rim or binding to the box form with a dovetailed effect. Fig. 11 is a vertical section of the punch showing the means for operating the same as well as the mechanism for pinching the binding about the box form. Fig. 12 is an inverted plan view of the punch or plunger. Fig. 13 is an enlarged view, partly broken away and partly in section, showing the clencher mechanism. Fig. 14 is an enlarged fragmentary section of the punch 10 and parts in their normal position. Fig. 15 is a fragmentary section of a part of the punch or plunger. Fig. 15^a is a fragmentary sectional plan showing how two screws of the punch may be held from turning. Fig. 16 is an inverted plan of the punch and clencher mechanism partly broken away. Fig. 17 is a view of a spring clip or latch for the metal binding. Fig. 18 is a fragmentary section, partly in elevation, of a 25 fixed form of latch or catch for holding the lapped ends of the binding prior to clenching the same to the box form. Fig. 19 is a fragmentary elevation of the form of latch shown in Fig. 18; and Fig. 20 is an inverted 30 side elevation of the cam portion on one of the clenching members which is adapted to depress one of the folders for the metal strip while the strip is being forced about the anvil or former.
- 35 While the invention is ordinarily applied to a particular form of machine, it will be understood that many of the features may be used in connection with various forms of box or basket machines or alone, and 40 that some of the parts may be dispensed with or other features substituted therefor without departing from the spirit of the invention.
- In the general operation of an automatic 45 box-making machine to which this invention is particularly applicable, a narrow metallic strip is fed from a reel or otherwise suitably supported convenient to the machine, and this strip by suitable mechanism is fed to what may be termed forming mechanism, that is, the metal is bent or formed lengthwise thereof so as to be substantially V-shaped or U-shaped in cross-section in order to fit over the open edge of 50 the box form. This strip is fed inward and tilted and after being tilted so that it will assume a proper position relative to the edges of the box and the anvil or former about which it is bent according to the shape 55 of the box, the strip is then cut off the proper length. The strip is then fed forward on one side of a substantially rectangular anvil having a shape corresponding to the shape of the open end of the box 60 and until the said strip meets the anvil,

when the jaws into which the strip has been previously fed by engagement with the former or anvil will bend both ends of the strip on opposite sides thereof making the same substantially U-shaped. A second 70 pair of jaws engages the free ends of the binding strip and forces the same on the remaining side of the anvil and causes one end of the strip to overlap the other. The shooks of which the box body is made are 75 placed in two magazines located adjacent to one end of the machine, and these shooks are automatically fed upward in position to be removed therefrom. A reciprocatory and rotary pneumatic device is provided for 80 this purpose and this device is automatically controlled so that the shooks will be picked up first from one magazine and then from the other so that the shooks as thus picked up will lie crosswise and at substantially 85 right angles to each other. The pneumatic device discharges the crossed shooks into a rotary carrier or turret. A movement is given to the carrier and this places the crossed shooks in the path of box-forming 90 mechanism, and at the proper time this mechanism operates to form the shooks into box form and carries the box from above the carrier and forces the upper edge thereof into the binding strip. The binding strip is then pinched on to the shooks thus holding the box shooks permanently together in box form. Means is provided for stripping the box and causing the completed box to be deposited into the carrier, 100 and the carrier as it feeds new shooks crosswise to the die mechanism conveys the completed box into position to be discharged. The completed box is forced out of the carrier into a chute and properly stacked and 105 may be removed in any desired way. Another form of machine to which the invention is applicable is one in which two or more strips are used as a binding for each box or basket, or as already stated, the invention may be used simply as a hand operated or box body forming machine. 110

The veneer shooks are placed in a holder 10 in any suitable way between a punch or plunger 11 and the die 12. The holder 10 may be of any suitable kind or may be in the form of a carrier which is adapted to move the shooks in a crosswise position under the punch 11 and then to receive the completed box and move the same away 115 from the punch and die in substantially the manner described in connection with the application hereinbefore referred to. Instead of the movable holding means for the shooks as set forth in said application for 120 holding and alining the same, the said shooks may be sprung or forced between stationary grippers 13 and 14. There are two substantially L-shaped grippers 13 and 125 two similar grippers 14 arranged in opposed 130

relation and each has a retaining lip or bead 14^a. The sets of grippers 13 and 14 are so arranged that when the shooks are forced therein they will lie one at a higher level than the other so that any difference in their lengths will not cause the top shook to spring the one beneath it down so far that the latter will be away from its registered position in the grippers. These shooks 10 are indicated at 15 and 16 and are adapted, as will be hereinafter described, to be held between the plunger and die and to be moved by said plunger and die from the holder 10 and formed into box form.

15 The die and its operating mechanism, Figs. 1 and 4 to 14, comprises a head 17 substantially rectangular in form and having a concaved upper surface in which is seated a rubber gasket or pad 18 also substantially rectangular in form. This pad is held by a plate 19 which extends partly over the upper surface of said pad. The plate 19 has a central opening and through said opening extends a tubular screw 20, the threaded end 25 of which engages the threaded upper opening of a tubular member 21 in which suction may be created or a vacuum formed so as to create suction about the pad 18 as will be presently described. The screw 20 as 30 well as the upper surface of the plate 19 are each provided with radiating grooves adapted to communicate with the tube or member 21 so that suction may be created over substantially the entire surface of said 35 suction pad 18. At the outer edge of the pad 18 are yielding members 22. There are four of such members so as to make a substantially rectangular body when in position which corresponds substantially to the 40 shape of the box or berry basket bottom. These members 22 are substantially L-shaped in form and have one portion thereof movable in recesses 23 in the die head 17 and said members 22 are normally forced 45 outward by springs 24 located in said recesses 23, the outward movement of said members being limited by means of screws 25 or in any other desired way. The purpose of these yielding members 22 is to compensate for any irregularity in the length of 50 the shooks when inserted into the binding as will be described hereinafter, the said plates or members 22 yielding sufficiently to permit the sides of the box when folded to be 55 forced slightly downward in order that the upper edges of the box may be substantially straight and in order that the narrow metal binding may be properly held to the upper edges of the shooks to form the box.

60 A wing or member 26 is adapted to cooperate with each of the yielding members 22 and as there are four of the yielding members 22 and four ends of the shooks to fold there are also four wings 26. The ends 65 of the shooks which lie crosswise are adapt-

ed to have their outer ends rest on said wings 26 and at the outer edge of the wings are yieldingly held members, plates or parts 27 which have a relative movement and which are adapted to align or cause the shooks to be properly registered. The members 27 have a tongue-and-groove connection with the wings and are yieldingly forced outward by springs 28 or otherwise, said outward movement being limited by stops 28^a held to the inner surface of each plate 27 and adapted to engage the outer end of the wing on which the plate 27 moves. The springs 28 are located on the outside of the plates 27 and are interposed between lugs on said plates and lugs on the wings 26. The inner edges of the wings 26 are substantially semi-circular and are adapted to underlap the outer edges of the members 22 so that in their upward folding movement the said wings will pass about the outer edges of the said members 22 and with a lapping effect yieldingly hold and move about the shooks at the fold so that the latter cannot sliver or break even should the shooks be of cross-grained wood. The inner ends of the wings 26 are provided with recesses which receive the ends 29 of spring-pressed bolts 30. These bolts, two for each wing, have their lower ends passing through apertures in lugs 30^a on the die head, and around said bolts are springs 30^b tending normally to force the same outwardly and to yieldingly hold the inner edges of the wings 26 against the outer edges of the members 22, said springs having seats in recesses or concaved portions in the heads of the bolts 30 at one end, and having seats in the lugs 30^a at their other ends or in cup-shaped devices if preferred. A plurality of 105 spring clips 30^c are provided each having two retaining fingers which are adapted to partly span the heads of two of the bolts 30, there being a clip for each pair of bolts 30 of each wing. 110

To move the die upward and also to move the wings 26 to fold the shooks and form the sides thereof, various means may be employed. As shown, the wings 26 are provided with lugs 31 and connected to these lugs by pins 124 are links or arms 32, the latter being arranged in pairs. The lower ends of the arms 32 are connected by pins 32^a to a cross-head 33, the inner portion of which is provided with an opening in which is held a tubular member 34, the latter being arranged around the central tubular member 21 and being held to the cross-head 33 by means of a nut 35 or in any other desired way. Two links or arms 36 are connected to each pair of arms 32 at one end and to the die head 17 at the other end, and said links are adapted during the upward movement of the cross-head 33 to hold the arms 32 in such a manner as to cause the same to move 125 130

properly about the outer edge of the plates or members 22 during the folding operation. The cross-head 33 has outwardly extending arms 37, the outer portions of which are pivotally connected by tubular pins 38 to arms or links 39. The pins 38 are held to guide blocks 40 which are adapted to move vertically in guides 41 forming a part of a box-like structure 42, the said parts serving to prevent any rotary movement of the die as the same is moved upward. The lower ends of the links or rods 39 are connected to arms 43 and these arms are pivotally held to a shaft 44. These arms 43 are connected to be operated by an arm 45 which is connected to a link or rod 46. The rod 46 is connected at its lower end to an arm 47, and said arm is pivoted at 48 to the machine frame, said rod 46 being provided with a turnbuckle 49 by which the latter may be adjusted. The arm 47 is provided with a trundle 50 which is adapted to be operated by a cam 51 arranged on the drive shaft 52. The die head 17 has downwardly extending portions which are connected by tubular pins or thimbles 53 to the upper ends of links or rods 54. The lower ends of the rods 54 are connected to arms 55 and these arms are operated through an arm 56 which extends outwardly and moves about the shaft 44 as a pivot. The arms 56 is connected to a link or rod 57, the lower end of which is pivoted to an arm 58 which is adapted to rock on the shaft 48. The arm 58 like the arm 47 is provided with a trundle 59 which is adapted to be operated by a cam 60, said rod 57 being also provided with a turnbuckle 61 by which the latter may be adjusted. It will be evident that as the shaft 52 is rotated, the cams will operate the arms 47 and 58 and will move rods 46 and 57 so that the die head 17 and the cross-head 33 will move in unison and at the proper time during the upward movement owing to the character of the cams 51 and 60, the arms 32 will cause the wings 26 to be moved at an angle with respect to the upper surface of the die, thus forcing the ends of the shooks upwardly to fold the same. Instead of the particular mechanism described for operating the die, any suitable mechanism may be employed.

The punch 11 has a part thereof bodily movable downward toward the die so that the shooks may be held between the die and the punch and by the punch and die the shooks are carried upward and during such upward movement folded into box form. This punch 11 has a presser foot 62, a member 63, and a third member 64. The member 64 is held to a head 65 and about said head is an anvil 66 which is substantially rectangular in form and about which the metal binding strip is formed so that its open edges extend downward as shown best

in Fig. 10. The member 64 has yielding sides 67, the lower edges of which are provided with ribs 68 which are adapted to be seated in grooves in the upturned portions 69 of the body 70 of said member 64, though instead of said movable sides, the said member may be solid. Each side is normally pressed outward by one or more springs 71 and such outward movement is limited by one or more screws 72, the threaded portion of which is held in the body portion 70 of the member 64 and the head of which is seated in a bushing or cup-shaped cap 73 which may be spun into an opening in each wing or side 67 so that said sides may be permitted to yield properly under the pressure of the plates 27 and die wings or members 26 when the latter are forced to the position shown in Fig. 10. The screws 72 may be locked from turning, Fig. 15^a, by a ball 73^a which is arranged to engage the inner portions of two of the adjacent screws 72, said ball being forced inwardly by a screw 73^b at the same time forcing the unthreaded ends of the screws 72 against the unthreaded walls 73^c of the body 70. The member 64 of the punch has a relatively slight up-and-down movement, while the member 63 and presser foot 62 move toward the die and then upward again, although said presser foot 62 has a relative movement with respect to said member 63. This presser foot 62 has a body 74 substantially rectangular in form and while somewhat smaller corresponds to the shape of the bottom of the box or basket to be made and has a tubular stem 75 which is adapted to slide within the tube 76, there being a key or wedge 77 which passes through a slot 78 in the stem 75 and serves to draw the member 63 up tight on the tapered end of the tube 76. The presser foot serves as a stripper for the member 63 to keep the bent part of the shooks from wrapping around or adhering to said member when the latter comes out of the box when formed. The presser foot is normally forced downward by springs 79 arranged between the upper surface of the body 74 of said foot and a flange at the upper portion of the member 63, the said springs being arranged around rods projecting upward from the presser foot and which serve to hold the springs in position. The member 63 of the punch or plunger has a tapered opening centrally thereof which fits upon the tapered end of the tube or guide 76. The tubes 76 and 80 extend upward through a part 81 of the machine frame and at the upper end of the tube 76 is a yoke 82 which is rigidly held to the tube 76 and is adapted to have a vertical reciprocating movement imparted thereto by means of levers 83 or otherwise so that the member 63 with the presser foot 62 may be forced down to meet the die 130

and to engage the shooks and then to move upwardly with the die again carrying the shooks therewith. As previously stated, the shooks lie crosswise in the holder 10 so that 5 one will be at a higher level than the other in order that any difference in their lengths will not cause the top shook to spring the one beneath it down so far that the latter will be away from its registered position in 10 the fixed grippers 14. These shooks may be moved from the fixed grippers without breaking the ends thereof. The die should be closed to approximately thirty degrees, and said die in its upward movement passes 15 through the holder 10 and during such movement the ends of the shooks will draw in and will be freed from the grippers, it being understood that the punch co-operates with the die at this time. The die can 20 continue to rise and should there be any tendency for the shooks to slip more to one side than the other, a little tension bar, not shown, extending out of the die may be employed to hold the shooks between it and 25 the punch to keep the shooks from moving or revolving. The tube 80 has a collar or head 84 against which rests the upper end of a spring 85, the lower end of said spring resting against a part 86 of the frame portion 81. The spring 85 serves to force the tube 80 and the anvil 66 upwardly when released as will presently be described. 30

As the shooks are folded into box form as shown in Fig. 10, the upper edges thereof are received in the open portion of a substantially rectangular metal binding substantially U-shaped in cross-section which is held and supported in any suitable way about the anvil 66, the particular construction 35 of anvil and the means whereby the strip or strips are formed rectangularly thereabout, not forming a part of the present invention, may be of any desired construction or may be such as disclosed in the 40 application herein referred to. After the metal binding has received the upper edges of the box form, suitable clencher mechanism, as 87, may be employed to clench or crimp the narrow metal binding about the 45 edges of the box form. As one means, I provide levers 88 which may be pivoted, at 50 89, to a head 90 or part of the frame, and at their lower ends, said levers carry adjustable presser or clencher jaws 91. The 55 upper ends of these levers 88 may be held by springs and have a toggle connection with the sleeve 92 by means of links 93, said links being kept from coming out by screws 93^a. The sleeve 92 is independently movable upon the tube 80 by means of levers 94 or otherwise so that at the proper time 60 the metal strip or strips about the anvil is forced into locking engagement with the box form. 65 After the strip is clenched about the box

body, the die is lowered and as the die is lowered the box or basket is carried therewith and may be deposited into four corner holding members 94^a, Fig. 1, substantially Y-shaped in form and mounted in the holder 70 10 15 20 25 30 35 40 45 50 55 60 65 70 75 80 85 90 95 100 105 110 115 120 125 130

75

shown, the suction pad 18 which is held by means of the plate 19 and tubular screw 20 against the die head 17 is adapted to fit snugly against the bottom of the basket and suction is created within the tube 21 in such a way and at such a time that the basket will be caused to be held to the bottom of the die and with the assistance of the presser foot 62, the said basket when completed will be forced or stripped from the punch. The 80 tubular screw 20 has radial slots 95 which are adapted to register with slots 96 in the plate 19 so that when suction is created within the tube 21, air may be drawn through said slots 96 to create sufficient 85 suction to hold the box shooks to the die bottom and said suction should be destroyed at the proper time to adapt the box to be removed automatically or otherwise. The tube 21 is provided with an opening 97 and 95 this opening is adapted to register with an opening 98 in a tube 34 arranged around said tube 21. The tubes 21 and 34 are movable in a tubular part 99 of the machine frame. This tubular part 99 has an 100 extension 100 to which may be connected an exhaust pump and within the member 99 around the tube 34 is a chamber 101. This chamber 101 is adapted to be placed into communication with the openings 97 and 98 105 to cause suction about the box or box material as shown in Fig. 3. The suction or vacuum is adapted to be destroyed by a relative movement between the tubes 21 and 34 as shown in Fig. 2, and a small opening 110 101^a in a plug 102 located in the bottom of the tube 21, which opening is of such a size as will not injuriously affect the suction means while in operation and while the ports or openings 97 and 98 are in alignment 115 but which will destroy any vacuum in the tube 21 as soon as the suction means is cut off, there being an adjustable thimble or sleeve 102^a provided whereby the time when the suction is destroyed through the opening 98 may be properly timed. Instead of the ports and the parts as shown, any suitable means may be employed to create or destroy the suction or vacuum. 120

There are two hooks or catches 103 and 104 which are located adjacent to the punch and which are supported adjacent to the anvil about which the metal binding whether a single or double strip or two strips is adapted to be formed to substantially the 130

shape of the open end of the box form. These hooks are adapted to sustain and hold the ends of the binding metal, the hook or catch 103 being yielding and the hook or catch 104 being normally fixed. There may be as many of these hooks of either the yielding or fixed kind or both kinds as desired. The hook 103 has an elongated shank portion 105 which is adapted to fit 10 into a circular socket 106 and is pivoted, at 107, at the inner portion of the socket 106 to adapt the outer or hooked end 108 to move up-and-down. The hooked end 108 has a lip 109 which is adapted to engage 15 under one edge of the metal binding and the shank 105 of the device is provided with a slot 110 which is adapted to form a seat for a part 111 of a spring 112. The socket piece 106 is cut away to permit proper up-and-down movement of the hook 103 and is held 20 therein against outward movement by one end of a plate which is held in place by a flat screw or otherwise. At the inner end the socket piece is adapted to abut against 25 the head of a screw 113 by which the position of the socket 106 may be determined. As one free end of the metal binding is forced about the anvil, it will raise the hooked end 108 to pass by the same and 30 when against the anvil the end 108 will be forced downward and the lip 109 will engage under the lower edge of the binding. The other free end of the binding during the folding operation about the anvil is adapted 35 to have its free end forced downward by a cam 114, Figs. 16 and 20, located on one of the clencher levers 88 in substantially the same manner as described in the application herein referred to, the free end of the 40 strip being forced down far enough to pass under the free end of the binding held by the hook 103 and to enter a recess 115 between the anvil and the lip 116 of the end 117 of the hook or catch 104. At this time 45 the end of the binding will overlap and when the plunger mechanism has been operated as already described, the compression of the metal binding to grip the upper edges of the box form will cause the edge held by 50 the lip 116 to pass therefrom so that the completed box may be stripped from the punch without the hook 104 or the hook 103 interfering in any way with the metal binding. The hook 104 has a shank 118 and is 55 held in a square box 119. This box fits a similarly shaped socket located over the former or anvil 66 and said box is adjusted outwardly by means of a screw 120. The box 119 has one edge thereof provided with 60 a tapered recess and adapted to engage this recess is a tapered screw 121 by which the box is held against removal. The metal binding is thus held in position to receive the upper edge of the box form during the 65 upward movement of the die and punch, and

as soon as the binding has been clenched to the box form and the jaws 91 receded from their clenched position, the die is lowered. The die waits for the box and the punch and die go down together, the die wings 26 70 remaining folded around the same during the descent of the die. This condition exists until the die bottom is down and the box or basket is lodged in the holding members 94^a, after which the wings quickly open flat. 75 This folded up relation of the wings in the descent assists materially in stripping the box from the punch.

If the machine is automatic the turret or holder 10 carries the box or basket to an 80 ejector.

It is desirable that the four folding wings or members of the die be independently adjustable so that they will coöperate properly with relation to the punch and the anvil. This means of adjustment may be of any suitable kind. As shown, Figs. 5 to 7, the arms 32 are arranged in pairs and spaced apart at their upper ends by a spool 122 and are held in such spaced position by a screw 123, a tube 124 serving as a shaft or pivot for connecting the arms 32 to the wings 26. The links 36, there being two for each wing, are held to a spool or spacer 125. The spacer 125 has threaded portions 126 90 on which are spanner nuts 127, the latter having recesses to permit the shank of a screw 128 to engage the same, the shank of the screw passing into one of the links 36 thus preventing the nuts from unscrewing. The spool or spacer oscillates upon an eccentric pin or shaft 129 which is held against rotary movement in the arms 32. This shaft 129 has one end provided with a nut 130 and its other end with a cap or collar 131. This cap or collar is provided with a plurality of openings 132 in one of which is adapted to pass a screw 133, the shank of which is screw-threaded and engages an aperture in one of the arms 32, 95 thus the shaft or pin 129 may be variously positioned so that the arms or links 32 may be adjusted relatively to the die head 17 in order that the wings may have the right relation to the anvil and to be moved for 100 adjustment independently of each other. The eccentric shaft or pin 129 may have an oil passage 134 whereby the spool or spacer 125 may be properly lubricated.

If it is desired to remove the anvil 66 and 120 head 65 for repairs or other purposes, this may be done very readily by releasing the screws 135 which hold the tube 80 to the sleeve 136 which supports the anvil. The lower end of the tube 80 is threaded and 125 engaging said threaded end is a spanner nut 137. By removing the pin 77, the presser foot may be removed and the punch 63 may be removed which will release the punch member 64 so that the anvil may be removed 130

and afterward reinserted in the machine as desired.

The sleeve 138 serves as a bearing for the reciprocatory tube 136, but is intended more particularly for a stop for the upward return of the anvil head 65. This stop being adjustable, allows the wire rim or metal binding which is held on the anvil and not yet clenched on the box body to bear different vertical relations to the clenching jaws 91 and thus affects the clenching of the binding either high or low on the side of the rim or binding itself. This allows of easy adjustment to cause the jaws 91 to clench the lower edge only of the U-shaped metal rim on to the wood shooks leaving the upper or top portion of the section of the U-shaped binding and wood unflattened. By this means, a novel method of making a very strong and practical fastening of the metal to the wood is secured. The shape of this fastening is on the principle of the engagement of a dovetail, as at 138^a, Fig. 10^a, and allows the wood to shrink away from the metal and yet not pull out of the dovetail in the metal. Wooden shooks, it might be mentioned, have to be worked in a damp state and always shrink thereafter, especially when made of sweet gum. The adjustment of the sleeve 138 is secured by turning the same by means of spanner slots 139 and then setting up the lock nut 140, said sleeve 138 being threaded at its upper end 141 and engaging a threaded bore 142 in the frame 90. The lower end or stop end 143 engages with a portion 144 of the head 65 for the anvil 66, there being a clearance space to allow adjustment between the head 90 and the stop end 143. The head 65 and the anvil are moved to its lowered position against the tension of the spring 85 by the sleeve 92 to place the anvil in alignment with the folding jaws of the metal bending mechanism, the anvil being raised by the spring 85 as the sleeve 92 is elevated to move the clenching levers 88 and jaws 91 to clench the binding to the box form.

While the anvil and some of the parts coöperating therewith are shown in more or less detail, these parts as well as the mechanism for bending the metal rim or binding about the anvil relate more particularly to metal bending and form only in a general way or broadly a part of the invention of this application. A complete description, therefore, of such parts is thought unnecessary. It might be well to mention however, that the head 65 has ledges 145 which serve to keep the shooks when folded into box form from pushing the rim or binding up off the anvil 66. The casting 146, Fig. 10, has bosses 147, Fig. 14, at its four corners and said bosses have apertures in which are pivot pins 148 for the folders of the bending

mechanism to swing around. There are also bending edges 149, Fig. 16, adapted to co-operate with the folding means to form the corners of the rim or binding.

All of the hollow pins may be made to serve as oil reservoirs by closing the ends thereof with plugs 150, one of which is provided with a vent or oil opening. The pins 124, Fig. 5, are split back to receive tapered pins which, when the latter are driven in, spread the ends of said pins making a tight fit in the ears of the wings 26. One of the plugs 150 of each pin may have a vent or oil opening 151, the vent or oil opening of the plug being positioned so that the hollow pin or shaft may be filled about two-thirds full of oil. The plugs may be removed by inserting a rod through the opening 151 to drive out the solid plug and then the vented plug may be driven out from the open end of the pin. The eccentric pins 134 may have threaded plugs in their ends, one plug of each pin having an oil hole and the pins 81^a may also have similar or other plugs as well as the pins 89 of the clencher levers, there being an outlet opening in each instance for the oil to pass to the bearings.

From the foregoing, it will be evident that effective means are provided whereby boxes or baskets of various sizes may be made and a metal binding applied; that simple means is provided whereby cross-grained shooks may be utilized and folded without breaking at the point of fold; that simple means is provided whereby irregularities in the lengths and thickness of the shooks may be compensated for; that effective die and punch mechanism is provided in which the parts are properly adjustable with relation to each other; that said parts are readily accessible for repairs or for other purposes; that simple and efficient pneumatic means is provided to assist in stripping the box when completed from the punch; and that said mechanism is of such a character that parts thereof are adapted for use in connection with an entirely automatic machine or in a machine which is only partly automatic or of a hand-operative kind.

Having thus described my invention, I claim as new and desire to secure by Letters Patent:—

1. In a box-making machine, the combination of a reciprocatory punch, and a die having wings the inner edges of which are free and yieldingly held against and adapted to move with a lapping effect about a part of said die.

2. In a box-making machine, the combination of a punch, and a die having folding members yieldingly held against a part of said die and having a rolling lapping effect about said part.

3. In a box-making machine, the combination of a punch, and a die having yielding

parts forming a part of the base of said die, and wings the inner edges of which are held against said yielding parts.

4. In a box-making machine, the combination of a reciprocatory punch, a die having a head and a supporting part for shooks substantially the size of the bottom of the box to be made, wings in a normal position located in substantially parallel relation to the supporting part of the die and having their inner edges yieldingly held to move about the outer edges of said supporting part, means for moving the die bodily with the wings, and means whereby the wings may be moved at an angle with relation to the supporting part of the die and in such a way that the shooks are positively held at the place where they are folded to prevent breaking thereof.
5. In a box-making machine, the combination of a punch, a die having a supporting part for shooks substantially the size of the bottom of the box to be made, wings having their inner edges yieldingly held to move about the outer edges of said supporting part, and means whereby the wings may be moved at an angle with relation to the supporting part of the die with a lapping effect so that the shooks are positively held at the place where they are folded.
6. In a box-making machine, the combination of a die having a supporting part for shooks substantially the size of the bottom of the box to be made, wings held to move about the outer edges of said supporting part, means whereby the wings may be moved at an angle with relation to the supporting part of the die with a lapping effect so that the shooks are positively held at the place where they are folded, and means co-operating with the die to fold shooks box form.
7. In a box-making machine, the combination of a punch, a die having a head and a supporting part for shooks substantially the size of the bottom of the box to be made, four wings in a normal position located in substantially parallel relation to the supporting part of the die and having their inner edges yieldingly held to move about the outer edges of said supporting part, and means whereby the wings may be moved at an angle with relation to the supporting part of the die and with a lapping rolling effect so that the shooks are positively held at the place where they are folded.
8. In a box-making machine, the combination of a die having a head and a substantially rectangular supporting part for shooks substantially the size of the bottom of the box to be made, four horizontally arranged wings having their inner edges yieldingly held to move about the outer edges of said supporting part, means for moving the die bodily with the wings, means whereby

the wings may be moved at an angle with relation to the supporting part of the die and with a lapping rolling effect so that the shooks are positively held at the place where they are folded, and means co-operating with the die to fold shooks box form.

9. In a box-making machine, the combination of a punch, means for supporting a metal binding adjacent to the punch, a reciprocatory die movable toward and away from the punch and adapted to move with the punch at one period of their movement to carry shooks bodily, a holder interposed between the die and the punch adapted to hold shooks crosswise and to have the shooks removed bodily therefrom during the movement of the die and punch, means for creating suction to assist in stripping the box when completed from the punch, means whereby the suction may be destroyed, together with means whereby the metal binding held about the punch may be caused to be held to the box body.

10. In a box-making machine, the combination of a punch, means for supporting a metal binding adjacent to the punch, a die movable toward and away from the punch and adapted to move with the punch at one period of their movement to carry the shooks bodily, a holder interposed between the die and the punch adapted to hold shooks crosswise and to have the shooks removed bodily therefrom during the movement of the die and punch, means for creating suction to assist in stripping the box when completed from the punch, together with means whereby the metal binding held about the punch may be caused to be held to the box body.

11. In a box-making machine, the combination of a reciprocatory punch, a reciprocatory die movable toward and away from the punch and adapted to move with the punch at one period of their movement to carry shooks bodily, a holder interposed between the die and the punch adapted to hold shooks crosswise and to have the shooks removed bodily therefrom during the movement of the die and punch, and means for creating suction to assist in stripping the box when completed from the punch.

12. In a box-making machine, the combination of a punch, a die movable toward and away from the punch and adapted to move with the punch at one period of their movement, a holder interposed between the die and the punch adapted to hold shooks crosswise and to have the shooks removed bodily therefrom during the movement of the die and punch, and means for creating suction to assist in stripping the box when completed from the punch.

13. In a box-making machine, the combination of a punch, a die having a head with yielding portions adapted to support

shooks at a point forming the outer surface of the bottom of said box when formed, a rubber pad, a retaining grooved plate, a tubular screw member, means for creating suction in said tubular member, and means for folding the shooks.

14. In a box-making machine, the combination of a punch, a die having a head with yielding portions forming a part of the base thereof adapted to support shooks at a point forming the outer surface of the bottom of said box when formed, and means movable about the outer edges of said yielding portions for folding the shooks.

15. In a box-making machine, the combination of a punch, a die having a head adapted to support shooks, a rubber pad, a retaining grooved plate, a tubular screw member, means for creating suction in said tubular member, and wings for folding the shooks.

16. In a box-making machine, the combination of a punch, a die having a head provided with portions adapted to support shooks, a rubber pad, retaining means, means for creating suction, and means for folding the sides of the shooks.

17. In a box-making machine, the combination of a die having a head provided with yielding members, wings yieldingly held to move about said members at the point where the shooks are folded, yieldingly held ends to compensate for the inaccuracies of alinement and thickness of the shooks, means for moving the head and wings together and to move the wings angularly with respect to the head and independently thereof, and a punch coöperating with the die to form the box body.

18. In a box-making machine, the combination of a die having a head, wings held to move about said head where the shooks are folded, yieldingly held ends mounted on the wings to compensate for the inaccuracies of alinement and thickness of the shooks, means for moving the wings angularly with respect to the head, and a punch coöperating with the die to form the box body.

19. In a box-making machine, the combination of a die having a head, wings, a yieldingly held and slidable end plate mounted on the outer end of each wing to compensate for the inaccuracies of alinement and thickness of the shooks, means for moving the head and wings together and to move the wings angularly with respect to the head, and a punch coöperating with the die to form the box body.

20. In a box-making machine, the combination of a die having a head provided with yielding members, wings yieldingly held to move about said members at the point where the shooks are folded, yieldingly held ends mounted on the wings to compensate for the inaccuracies of aline-

ment and thickness of the shooks, means for moving the wings, and a punch coöperating with the die to form the box body.

21. In a box-making machine, the combination of a die having a head, wings 70 yieldingly held to move about said members at the point where the shooks are folded, ends mounted on the wings to compensate for the inaccuracies of alinement and thickness of the shooks, means for moving the 75 head and wings together and to move the wings angularly with respect to the head, and a punch coöperating with the die to form the box body.

22. In a box-making machine, the combination of a die head having means to support shooks and corresponding substantially to the shape of the box body when formed, wings having their inner ends yieldingly held to move about said shook supporting 85 part of the die, an independently movable cross-head, arms connecting the cross-head to the wings, links connecting the arms to the die head, means for adjusting said links independently of each other, and a punch 90 coöperating with the die.

23. In a box-making machine, the combination of a die head having means to support shooks, wings having their inner ends held to move about said shook supporting 95 part of the die, a movable cross-head, arms connecting the cross-head to the wings, links connecting the arms to the die head, and a punch coöperating with the die.

24. In a box-making machine, the combination of a die having means to support shooks, wings having their inner ends yieldingly held to move about said shook supporting part of the die, arms connected to the wings, links connecting the arms to a 105 part of the die, means for adjusting the links independently of each other, and a punch coöperating with the die.

25. In a box-making machine, the combination of a die head having means to support shooks and corresponding in shape substantially to the box body when formed, wings having their inner ends yieldingly held to move about said shook supporting part of the die, an independently movable 110 cross-head, arms connecting the cross-head to the wings, links connecting the arms to the die head, and a punch coöperating with the die.

26. In a box-making machine, the combination of a die head having means to support shooks, wings having their inner ends held to move about said shook supporting part of the die, an independently movable cross-head, arms connecting the cross-head 125 to the wings, substantially horizontally arranged links connecting the arms to the die head, means for adjusting said links, and a punch coöperating with the die.

27. In a box-making machine, the com- 128

bination of a punch, a die having a head, wings forming a part of the die, arms connected to the wings, means connected to the arms for moving the wings, links connecting the arms to the die head, and means for adjusting said links.

28. In a box-making machine, the combination of a punch, a die having a head, four wings forming a part of the die, arms connected to the wings, means connected to the arms for moving the wings, and links connecting the arms to the die head.

29. In a box-making machine, the combination of a punch, a die having wings forming a part thereof, arms connected to the wings, means connected to the arms for moving the wings, links connecting the arms to a part of the die, and means for adjusting said links.

30. In a box-making machine, the combination of a punch, a die having a head and provided with foldable wings, a cross-head, arms connecting the cross-head to the wings and arranged in pairs, links connecting each pair of arms to the die head, means for spacing the links apart, an eccentric pin supported by each pair of arms about which one end of the links move, a collar by which said pin may be adjusted, said collar having a number of openings therethrough, and a screw adapted to pass through any one of said openings for holding the pin in its adjusted position.

31. In a box-making machine, the combination of a punch, a die having a head and provided with foldable wings, a cross-head, arms connecting the cross-head to the wings and arranged in pairs, links connecting each pair of arms to the die head, means for spacing the links apart, and an adjustable eccentric pin supported by the arms and forming a bearing for one end of the links.

32. In a box-making machine, the combination of a punch, a die having a head and provided with foldable wings, a cross-head, arms connecting the cross-head to the wings, links connecting the arms to the die head, and adjustable eccentric pins supported by the arms and forming a bearing for one end of the links.

33. In a box-making machine, the combination of a punch, a die having a head and provided with foldable wings, a cross-head, arms connecting the cross-head to the wings and arranged in pairs, links connecting each pair of arms to the die head, means for spacing the links apart, an eccentric pin supported by each pair of arms, a collar by which said pin may be adjusted, and means for holding the collar in the adjusted position.

34. In a box-making machine, the combination of a punch, a die coöperating with the punch to form a box body, means for moving the punch and die independently of

each other and together, a tubular member arranged substantially central of the die, and means for creating and destroying suction in said tubular member.

35. In a box-making machine, the combination of a punch, a die coöperating with the punch to form a box body, a tubular member arranged substantially central of the die, and means for creating and destroying suction in said tubular member. 75

36. In a box-making machine, the combination of a punch, a die coöperating with the punch to form a box body, means for moving the punch, a tubular member arranged substantially central of the die, and means for creating and destroying suction in said tubular member. 75

37. In a box-making machine, the combination of a punch, a die coöperating with the punch to form a box body, means for moving the die, a tubular member communicating with the outer surface of the die, and means for creating and destroying suction in said tubular member. 85

38. In a box-making machine, the combination of a punch, a die coöperating with the punch to form a box body, means for moving the punch and die, a tubular member communicating with the outer surface of the die, and means for creating suction 95 in said tubular member.

39. In a box-making machine, the combination of a die, a holder, a reciprocatory forming punch having a plurality of substantially rectangular and relatively movable members and an independently movable presser foot, means for supporting a metal binding adjacent to the punch, means for supporting shooks between the punch and die, and means for moving the punch and die 105 toward or away from each other and together during a certain period.

40. In a box-making machine, the combination of a die, a holder, a punch having a plurality of relatively movable members and an independently movable presser foot, means for supporting a metal binding adjacent to the punch, means for supporting shooks between the punch and die, and means for moving the punch and die toward 115 or away from each other and together during a certain period.

41. In a box-making machine, the combination of a die, holding means for shooks, and a reciprocatory plunger having a yieldingly held presser foot and two members independent of the presser foot and of each other. 120

42. In a box-making machine, the combination of a die, and a punch coöperating with the die to form a box body and having a box-like member, and sides yieldingly supported on said member about which the sides of the box body are formed. 125

43. In a box-making machine, the combi- 130

nation of a die, and a punch coöperating with the die to form a box body and having a box-like member, a presser foot, and four sides yieldingly supported on said member 5 about which the sides of the box body are formed.

44. In a box-making machine, the combination of a die, and a punch coöperating with the die to form a box body and having 10 a member, and sides yieldingly supported on said member about which the sides of the box body are formed.

45. In a box-making machine, the combination of a die, and a reciprocatory punch 15 having independently movable members, four sides pivotally supported at one edge to one of said members, springs seated in one of said members and normally forcing the sides outward, cup-shaped devices held 20 to said sides, and screws held to the member to which the sides are pivoted and having the heads seated in said cup-shaped devices and adapted to limit the outward movement of said sides.

46. In a box-making machine, the combination of a die, and a punch having independently movable members, sides pivotally supported at one edge to one of said members, springs seated in said members 30 and normally forcing the sides outward, and screws held to the member to which the sides are pivoted and adapted to limit the outward movement of said sides.

47. In a box-making machine, the combination of a die, and a reciprocatory punch 35 having movable members, four sides pivotally supported at one edge to one of said members, springs seated in one of said members and normally forcing the sides outward, 40 and means held to the member to which the sides are pivoted and adapted to limit the outward movement of said sides.

48. In a box-making machine, the combination of a punch having a plurality of 45 members, tubular parts fitting one within the other and extending from said members and of relatively different lengths, screws for securely holding two of said tubular members at one end, and a spanner nut secured at the other end of one of said tubular members and adapted when removed together with the releasing of the said screws to permit the removal of certain parts.

49. In a box-making machine, the combination of a punch having a plurality of 55 members, an anvil, parts extending from said members, means for securely holding two of said parts at one end, and a nut secured at the other end of one of said parts 60 and adapted when removed together with the releasing of the said means to permit the removal of said anvil.

50. In a box-making machine, the combination of a punch having a plurality of 65 members, tubular parts extending from

said members, screws for securely holding two of said tubular members to one end, and a spanner nut secured at the other end of one of said tubular members and adapted when removed together with the releasing 70 of the said screws to permit the removal of certain parts.

51. In a box-making machine, the combination of a die, a punch coöperating with said die, a vertically movable sleeve having 75 a head to which a part of the punch is held, means for moving the sleeve vertically, an anvil supported on the head of said sleeve, a support in which the sleeve moves, a tubular member arranged in the support and 80 adapted to limit the upward movement of said sleeve and head, together with a clenching mechanism with respect to which the anvil and head are adapted to move.

52. In a box-making machine, the combination of a die, a punch coöperating with said die, a vertically movable sleeve having 85 a head to which a part of the punch is held, means for moving the sleeve vertically, an anvil supported on the head of said sleeve, 90 a support in which the sleeve moves, an adjustable tubular member arranged in the support and adapted to limit the upward movement of said sleeve and head, together with a clenching mechanism coöperating with 95 the anvil to place a binding about a body.

53. In a box-making machine, the combination of a die, a punch having a plurality of independently and vertically movable members, and a stop for limiting the upward movement of one member of said 100 punch.

54. In a box-making machine, the combination of a die, a punch coöperating with said die, a vertically movable sleeve having 105 a head to which a part of the punch is held, means for moving the sleeve vertically, a support in which the sleeve moves, and an adjustable tubular member arranged around 110 said sleeve and adapted to form a stop and limit the upward movement of said sleeve and punch member.

55. In a box-making machine, the combination of a die, a punch having a plurality of relatively movable members coöperating 115 with said die, a vertically movable sleeve having a head to which a part of the punch is held, means for moving the sleeve vertically, an anvil supported on the head of said sleeve, a support in which the sleeve moves, a tubular member having a threaded end 120 engaging a threaded bore in said support and adapted to limit the upward movement of said sleeve and head, and a nut for locking the tubular member in its adjusted position.

56. In a box-making machine, the combination of a die, a punch coöperating with said die to form shooks into box form, movable wings forming a part of said punch, 130

screws for limiting the outward movement of said wings, a ball, and a screw for moving the ball to engage two of the limiting screws for the wings to hold the same against unscrewing.

57. In a box-making machine, the combination of a die, a punch coöperating with said die to form shooks into box form, movable wings forming a part of said punch, 10 screws for limiting the outward movement of said wings, and means for engaging two of the limiting screws for the wings to hold the same against unscrewing.

58. In a box-making machine, the combination of a die, a punch coöperating with said die to form shooks into box form, movable wings forming a part of said punch, screws for limiting the outward movement of said wings, balls and screws for engaging the inner end of the limiting screws for the wings to hold the same against unscrewing.

59. In a box-making machine, the combination of die mechanism, punch mechanism coöperating therewith and each provided with movable members having hollow

pins forming pivots for said movable parts, and plugs arranged in the ends of each of said hollow pins, one of which is provided with an opening whereby each hollow pin 30 may be made to serve as an oil reservoir.

60. In a box-making machine, the combination of die mechanism, punch mechanism coöperating therewith and each provided with movable members having hollow 35 pins forming pivots for said movable parts, and means whereby the hollow pins may be made to serve as oil reservoirs.

61. In a box-making machine, the combination of die mechanism, punch mechanism coöperating therewith and each provided with movable members having hollow pins forming a pivot for said movable parts, and means arranged in the ends of each of 40 said hollow pins whereby each hollow pin 45 may be made to serve as an oil reservoir.

This specification signed and witnessed this 25th day of January A. D. 1915.
